UNITED STATES PATENT OFFICE.

CHARLES F. PYM, OF DETROIT, MICHIGAN, ASSIGNOR TO KRENTLER-PYM MACHINE COMPANY, OF DETROIT, MICHIGAN, A CORPORATION OF MICHIGAN.

METHOD OF MAKING BOOTS OR SHOES.

1,126,271.

Specification of Letters Patent.

Patented Jan. 26, 1915.

Application filed June 7, 1913. Serial No. 772,236.

To all whom it may concern:

Be it known that I, CHARLES F. PYM, a citizen of the United States of America, residing at Detroit, in the county of Wayne and State of Michigan, have invented certain new and useful Improvements in Methods of Making Boots or Shoes, of which the following is a specification, reference being had therein to the accompanying drawings.

This invention relates to improvements in the manufacture of boots and shoes, and more particularly to the method of securing an upper in lasted or partially lasted position upon the end of a last.

It has been the usual practice in lasting boots and shoes to work the upper up around and over the end of a last and to then secure it in lasted position by drawing a binder into contact therewith around the end of the last and securing the ends of the binder by tacks or other suitable means, the binder being drawn into firm contact with the upper by pulling upon one or both of its ends. Where wiper plates are employed to form an upper down upon a sole upon the last, it is necessary to relieve the downward pressure of the wipers upon the edge of the upper in order that the binder may be drawn beneath them into engagement with the upstanding edge of the upper, and if the wiper plates be raised sufficiently to permit the binder to slip freely into place, the upper will be released and will be liable to slip from the position to which it has been carried by the wipers, before the binder can be drawn sufficiently tight to hold it. If the wiper plates are not raised sufficiently to prevent the free seating of the binder upon the upper beneath them, a heavy strain upon the wire will be necessary to draw it firmly to place about the end of the last. In many instances this strain will be so great as to break the wire, and in any event it is necessary to use a wire or binder having considerable strength. The heavier the binder is the more it will interfere with the operation of sewing the upper to the sole and it is therefore advantageous to be able to use a binding wire or light gage.

One of the objects of this invention is to provide a method of positioning a binder which is such that said binder will be forced into firm contact with the formed upper to

hold the same firmly and accurately without subjecting the binder to any strain, said binder being laid in place while slack, if so desired, and therefore when a wire is used as a binder it may be of very light gage so as to form no hindrance to the operation of sewing the upper to the sole.

It is also an object of the invention to so lay the binder in place that the same will conform perfectly to the shape of the last and firmly clamp the upper against the last all the way around the end portion thereof when the binder is applied to other portions of the upper than that edge thereof which is adapted to be formed over and down upon a sole on the last.

For the purpose of illustration and that the invention may be more clearly understood, means are shown in the accompanying drawing for carrying out the method embodying this invention, but it will be understood that any suitable apparatus may be used or the invention practised by the use of suitable hand operated tools or devices. It will therefore be understood that this invention is in no way limited to the means shown for practising it or to the use of any particular machine, device or apparatus, but consists in the method hereinafter more fully described and pointed out in the appended claims.

Referring to the drawings, Figure 1 is a side elevation, partly in section, of a portion of a lasting machine having means for laying a binder to place about the end of a last according to the method embodying this invention; Fig. 2 is an inverted plan view of the same with the last removed; Fig. 3 is a front elevation of Fig. 1 with the last removed; Fig. 4 is a view similar to Fig. 1 showing a modified form of binder and roller for laying it in place; Fig. 5 is a plan view of a last with an upper in lasted position thereon and illustrating the manner in which rolls are employed to lay the binder in place; Fig. 6 is a perspective view of a lasted shoe held by a wire binder; and Fig. 7 is a similar view showing the binder illustrated in Fig. 4.

In practising this invention, after the lasting operation has been wholly or partially completed and it is desired to secure the upper in lasted position upon the last, a binder is placed adjacent to the end of the

last and then laid into firm even contact with the upper around the end of the last by pressure applied progressively thereto along its length to force it into contact at every point around the end of the last with the upper to be held by it.

Heretofore binders for holding the upper in lasted position have been placed by putting them under tension and drawing them 10 while under tension, closely about and into engagement with the upper. In the method embodied in this invention it is unnecessary to put the binder under tension at any time as it is laid into firm, even contact with the 15 upper throughout the length of the portion to be held by it by bringing suitable means into yielding contact with a portion of the binder and then moving said means along the binder to successively lay other portions 20 in place, thus accurately positioning the binder and taking out all kinks or slack by forming it down upon the upper with a progressive movement. Said binder may then be made fast to the last at its ends in 25 any suitable manner, it being understood that the means for or manner in which the binder is secured in place after being laid in binding position, is immaterial in the method embodying this invention.

30 As illustrating one means for carrying out the method embodying this invention in combination with a lasting machine having wiper plates for forming the upper around and against the end of a last, mechanism is 35 shown in the accompanying drawings comprising a pair of rolls 1 adapted to lie closely against the under surface of the wiper plates A which are carried within a slot in a carrier B supported upon a tiltable head C which in turn is carried by and has a movement upon a rocker D, all arranged in a suitable manner to give the proper wiping movement to the wiper plates. The rolls 1 are pivotally attached to the upper ends of 40 posts 2 to turn freely thereon and these posts are secured to the forward ends of arms 3 which are pivotally attached at their rear ends to a block 4 slidable upon a suitable guide 5 which is carried by and movable 45 with the rocker D and head C. The forward ends of the arms 3 are supported by suitable rolls 6 extending laterally from the guide 5 so that the arms may swing freely toward and from each other and have a longitudinal 50 movement forward and back when the block 4 is moved forwardly upon the guide 5 against the action of a coiled spring 7 upon the guide. The block may be moved against the action of the spring 7 in any suitable 55 manner as by cables 8 passing over sheaves 9 and downward to a suitable foot pedal (not shown).

60 Each of the rolls is preferably formed with an extended flange 10 at its upper end 65 and a smooth shank or body portion 11.

The flange is preferably formed with a very slight groove in its edge face and the body portion of the roll is preferably formed to meet the under side of the flange in a slight outward curve so that said body will approximate in form the outer surface of the shoe upper E adjacent to the edge of the shoe sole F upon the last G. The flange 10 of the roll is preferably of a width substantially equal to the distance which the 70 upper is laid over and formed down upon the edge of the sole. 75

In the operation of the machine, when the lasting operation has been completed and the wiper plates have wiped the upper around 80 the end of the last and formed it down upon the edge of the sole, a binding wire of suitable length is placed across the end of the last between suitable means, such as spring fingers 12, and the lower surface of the 85 wiper plate so that said binder will be held in position to be engaged by the flanges of the rolls and enter the grooves in said flanges when said rolls are brought forwardly into 90 engagement with the end of the shoe by the forward actuation of the block 4. The advance of the rolls forces their flanges in between the wiper plates and the formed down edge of the upper, carrying the wire over 95 said edge, and as the flange on each roll is 100 of a width substantially equal to the distance at which the lip is located from the edge of the sole, said wire will be laid into the angle in the edge of the upper which is formed by pressing it down hard upon the edge of the sole and against the lip. Upon 105 further forward movement the rolls will be spread apart by the last as they pass along the sides of the end portion thereof, the arms 3 being free to swing in opposite directions against the action of a suitable coiled spring 13 connecting them. The rolls are thus first forced into contact with the end 110 of the shoe to bring the binder against the same and they then lay the wire firmly in place as they proceed along the sides of the last from the end thereof with which they are first brought into engagement, at the same time contacting the formed over edge 115 of the upper and operating to smooth and form said edge. The binder is therefore first forced into place intermediate its ends against the end of the shoe and then progressively laid into place along each side of the end portion of the shoe throughout 120 the length of that portion of the upper which is to be held thereby. One or more rollers or other devices may of course be employed, and such device or devices may be brought into engagement with the binder 125 at any desired point and the binder may be laid in place by moving said device or devices as described or passing them around the end of the last from one side to the other thereof. The binder is laid firmly and 130

evenly in place in this manner without putting any strain upon it whatever and it may be placed in the machine with its ends perfectly free. After being laid in place by 5 the rollers, the ends of the binder may be made fast to the sole in the usual manner.

In Figs. 4 and 7, a flat binder is shown and this binder is laid in contact with the outer surface of the upper in its partially 10 lasted position. To lay a binder of this type in place, substantially plain rolls 14 may be employed to engage the outer surface of the flat band or binder 15 and press it firmly into contact with the surface of the upper. 15 After being so laid into place its ends may be secured in any suitable manner. Obviously the flanged rollers may, in certain instances, be used to lay a flat binder in place and if found desirable the rolls 14 may 20 be formed with a slight flange 16 at their lower ends to engage the lower edge of the binder and guide the same to place while laying it against the surface of the upper. Any suitable means such as spring fingers 25 17, may be employed to hold the band with its upper edge in contact with the lower surface of the wiper plates, and it is obvious that these spring fingers may be carried by the posts upon which the rolls are mounted, 30 to travel with the rolls, or may be supported from any other suitable part of the machine. It is obvious that this method of placing the binder while the same is in a slack condition, by laying portions thereof successively in 35 place as distinguished from holding it under tension and drawing it about the end of the last, may be carried out by hand or by means of suitable tools independently of the operation of a lasting machine or in conjunction 40 therewith as shown. This method relieves the binder of all strains, obviating the liability of its being broken and lays the binder firmly into place throughout its length so that the same will conform accurately 45 to the shape of the end of the last and firmly hold the upper in place.

Having thus fully described my invention what I claim is:—

1. The improvement in the art of making 50 boots and shoes which consists in placing and loosely holding a binder adjacent to the end of an upper upon a last and then laying said binder into position against the upper to hold the same in position upon the last, 55 by applying pressure successively to different portions of said binder while said binder is loosely held in a slack condition.

2. The improvement in the art of making 60 boots and shoes which consists in placing and loosely holding a binder with an intermediate portion thereof adjacent to the end of an upper upon a last, and then forcing 65 said intermediate portion of the binder into contact with said end of the upper and thereafter laying the portion of the binder

at each side of the intermediate portion into contact with the upper along each side of and adjacent to said end by applying pressure successively to different portions of the binder while the same is slack.

70

3. The improvement in the art of making boots and shoes which consists in working an upper into lasted position against the end of a last, placing a binder adjacent to said end of the last and forcing the binder into contact with the lasted portion of the upper progressively along each side of the last from the end thereof by pressure upon the opposite side of the binder.

75

4. The improvement in the art of making 20 boots and shoes which consists in working an upper into lasted position against the end of a last, placing a binder adjacent to said end of the last and forcing the binder into contact with the lasted portion of the upper 25 progressively along each side of the last from the end thereof, and simultaneously forming down the upper upon the last adjacent to the binder.

80

5. The improvement in the art of making 90 boots and shoes which consists in working an upper around and against the end of a last and over the edge of a sole upon the last into engagement with a lip of the sole and holding it in engagement therewith, and then 95 while the upper is so held laying by pressure upon its outer side, a binder into position to hold the upper in overworked position against the lip.

95

6. The improvement in the art of making 100 boots and shoes which consists in placing a binder with an intermediate portion thereof adjacent to the end of a last with the end portions of the binder extending laterally from the last, then bringing means for laying 105 the binder in a position for holding the upper, into contact with the intermediate portion of the binder and moving the same along the sides of the last from its position at the end thereof in contact with the laterally extending portions of the binder to lay 110 the same in contact with the upper around the end of the last.

110

7. The improvement in the art of making 115 boots and shoes which consists in working an upper around and against the end of a last, laying a binder into contact with the lasted portion of the upper around the end of the last by pressure and simultaneously forming the upper to the last along the edge 120 of a sole upon the last.

115

8. The improvement in the art of making 125 boots and shoes which consists in placing a binder adjacent to the end of a last having an upper in lasted position thereon and then laying the binder into contact with the lasted portion of the upper around the end of the last to hold the upper in lasted position, by engaging the binder at the end of the last and forcing the binder into engagement 130

130

with the upper by a rolling contact along each side of the end portion of the last from the end thereof.

9. The improvement in the art of making boots and shoes which consists in working an upper into lasted position around and against the end of a last, placing a binder adjacent to the end of the last, laying the binder upon the lasted portion of the upper 10 by a rolling contact with the binder throughout the length of the portion thereof adapted to contact the lasted portion of the upper, and then securing the ends of the binder to hold the same in the position in which it is 15 laid.

10: The improvement in the art of making boots and shoes which consists in working an upper into lasted position around and against the end of a last, placing and loosely 20 holding a binder adjacent to the end of the

last, laying a binder upon the lasted portion of the upper around the end of the last to hold the upper in lasted position, by forcing an intermediate portion of the binder into contact with the lasted upper at the end of the last, progressively forming the portions of the upper at each side of the intermediate portion into contact with the sides of the lasted upper adjacent to the end of the last by a rolling contact with the binder along 25 said portions, and then securing the free ends of the binder to the last while the binder is held in contact with the upper.

In testimony whereof I affix my signature in presence of two witnesses. 35
